UNITED STATES PATENT OFFICE

2,636,770

LIFTING AND CARRYING CLAMP FOR
HANDLING STONE SLABSTed Keith Cornwell, Cold Spring, Minn., assignor
to Cold Spring Granite Company, Cold Spring,
Minn., a corporation of Minnesota

Application December 8, 1950, Serial No. 199,856

1 Claim. (Cl. 294—103)

1

This invention relates to a lifting and carrying clamp for handling stone slabs.

It has been a considerable problem in erecting and handling large stone slabs such as marble for stone veneering and the like to provide efficient means for securely holding the gripping apparatus on the slab without damaging the highly polished surface or causing breakage of the slab and while permitting the slab to be lowered and placed directly into the desired position while still being supported from a flexible overhead supporting element.

It is an object of my invention to provide a slab lifting and erecting gripping clamp particularly adapted for use with highly polished hard-surfaced stone slabs and adapted to be supported from an overhead flexible hoist element and to be lowered thereby into the desired position.

It is another object to provide a slab-erecting clamp particularly adapted for use with highly polished hard-surfaced stone slabs and having a clamping jaw element with a slightly compressible stone-engaging surface fixed thereto and underlying a reinforcing pressure-applying element to equally distribute the clamping pressure over the relatively soft gripping surface.

More specifically, it is an object to provide a gripping clamp having a connector element adapted to be attached to a flexible overhead supporting member and having a stationary gripping element for engagement in a cooperating recess or slot provided in the rear unpolished side of a stone slab and a clamping jaw element having a reinforcing pressure-applying outer member with a slightly compressible polished surface-engaging gripping element underlying said pressure-applying element and producing sufficient friction against said highly polished surface to permit suspension of the slab solely by means of the gripping clamp alone to facilitate erection of the slab.

It is the combination of a shiftable, relatively large area gripping jaw having a rigid pressure-applying backing member with an underlying, slightly compressible gripping surface fixed thereto with a clamp having an upstanding attachment element for connection with an overhead flexible supporting member which permits a stone slab such as granite or marble to be tightly gripped along only the top marginal edge portion which facilitates the handling and erection thereof.

The above and other objects and advantages of the invention will more fully appear from

2

the following description made in connection with the accompanying drawings, wherein like reference characters refer to the same or similar parts throughout the several views, and in which:

Fig. 1 is a perspective view of my new gripping clamp in full lines showing a stone slab gripped thereby and supported for erection being shown in dotted lines;

10 Fig. 2 is a transverse vertical sectional view showing a stone slab securely gripped between the jaws of my gripping clamp with the overhead support member connected therewith.

15 As illustrated in the accompanying drawings, a gripping clamp, which in the form shown has a rigid, inverted, substantially U-shaped body 5, is provided, having the rear arm 5a and the front arm 5b rigidly interconnected by the supporting element 5c. A stationary gripping jaw

20 having the diminished projection 6 is fixed to the rear arm 5a and is adapted to engage the rear side of a slab such as the rear unpolished side of a slab 7. The slab has a recess or slot formed in the rear surface of the upper marginal edge portion and the diminished projection 6 of the stationary gripping jaw is constructed to be received in said recess.

25 A shiftable clamping jaw 8 is mounted on an elongated shiftable shank such as the threaded shank 9 which is threadably received through the front arm 5b as best shown in the accompanying drawings. The clamping jaw 8 is laminated with two layers being formed thereon. An outer pressure-applying layer in the shape of a disc 8a which is made from any suitable rigid material such as steel, wrought iron, or the like of sufficient thickness to uniformly distribute the pressure applied by turning the screw shank 9 through the arm 5b. A relatively soft, 30 slightly compressible lamination 8b is fixed under disc 8a and is substantially co-extensive therewith to engage the highly polished front surface of the slab 7. A relatively soft metallic material is preferably used for this lamination 8b such as lead or Babbitt material. The backing pressure applying element permits a sufficient surface area of relatively soft gripping material to be provided to prevent injury to the slab surface and to prevent possible cracking of the slab when gripping pressure is applied thereto.

35 An attachment ring 10 is connected to the supporting element 5c and is adapted to receive a hook 11 carried by a depending flexible supporting member such as the chain 12 which is, 40 45 of course, connected with any suitable hoisting

50

means such as a conventional block and tackle (not shown).

After long experimentation with the proper material to use for the engaging surface of the movable jaw, I found that a soft metallic material such as lead produced surprisingly satisfactory results. It is the slightly compressible quality of this surface-engaging jaw that gives it its high frictional resistance without damaging the highly polished surface or causing possible cracks in the veneered slab.

It will be seen that I have provided a relatively simple yet highly efficient lifting and carrying clamp for gripping stone slabs to facilitate handling and erection thereof. My clamp is provided with an attachment element adapted to be quickly and easily attached to a hook suspended from an overhead hoisting mechanism and to be supported solely thereby. The general combination of the reinforcing backing element with a slightly compressible gripping surface fixed thereto and means for tightly clamping said compressible surface against the highly polished front surface of a stone slab produces a clamp which is adapted to tightly grip and hold a stone slab solely by the medial portion of the upper marginal edge thereof. The specific combination of a clamp having a pair of spaced jaw members with a rigid, heavy, inverted, U-shaped body member interconnecting said jaws and having provision at the medial upper portion thereof for easy attachment to a hook suspended from a flexible overhead supporting element with means for clamping said two jaws together with the outer jaw being provided with a slightly compressible metallic gripping surface having a reinforcing rigid backing element fixed therebehind to permit secure gripping of a highly polished stone surface produces a lifting clamp adapted to greatly facilitate handling and erection of stone slabs and materially speeds up erection time, since the slab is suspended solely from the medial upper marginal edge portion thereof and permits the sides and bottom edges to be precisely positioned relative to the other slabs before the slab being erected is released from its overhead support. The rear stationary jaw 6 is relatively small to permit reception thereof in a recess or slot formed in the rear surface of the upper marginal edge portion of the slab.

It will, of course, be understood that various changes may be made in the form, details, arrangement and proportions of the various parts

without departure from the scope of my present invention, which, generally stated, consists in the matter shown, and described, and set forth in the appended claim.

5 What I claim is:

A lifting and carrying clamp adapted for use in handling and erecting stone veneering slabs for buildings and the like having one polished surface on the outer side thereof, said clamp comprising a rigid unyielding body member, a relatively thin stationary jaw fixed in depending relation at the rear end portion of said body and having an outwardly projecting interlocking element adapted to interfit with a cooperating recess formed in the back side of the slab, a shiftable clamping jaw mounted at the outer portion of said body and disposed in opposed relation to said fixed clamping jaw and forming the outer front jaw member of the gripping clamp, an unyielding pressure-applying backing plate on the outer front jaw member with a slightly compressible relatively soft metallic layer fixed on the backing plate for clamping engagement against the smooth polished outer slab surface, means mounting said shiftable clamping jaw on said body with provision for forcibly projecting said front jaw member toward the rear jaw member to tightly clamp said two jaws against the respective front and rear sides of the upper marginal portion of a stone slab to form the sole connection therewith and tightly hold the rear outwardly projecting interlocking element in interfitting relation within the cooperating recess in the back side of the slab, and an attachment element mounted on an intermediate portion of said body member.

TED KEITH CORNWELL.
